BUCKLE

Paul W. White, Waterbury, Conn., assignor to
 Parva Products Company, Chicago, Ill., a corporation of Delaware

Application July 1, 1942, Serial No. 449,237

12 Claims. (Cl. 24—194)

This invention relates to buckles, and more particularly to slide buckles adapted to be mounted on straps such as belts or the like for detachably securing or supporting garments or other articles, and the invention has for an object the provision of a slide buckle of this character which is of a light weight but sturdy construction, is inexpensive to manufacture and is effective to firmly clamp or readily release a strap as desired.

Slide buckles comprising a pair of slidably engaging sheet metal frames, having side bars and cross bars defining strap-receiving openings therethrough, have heretofore been proposed. Cross bars on the frames are arranged to clamp the strap threaded therebetween in adjusted positions. While many of such sheet metal buckles have been found highly satisfactory, the construction thereof is not such as to adapt them readily to manufacture from other materials, particularly materials having less unit strength and thus requiring greater thickness to provide a comparably sturdy buckle. Furthermore, in such sheet metal constructions the frames are usually retained in slidable relation with each other by bending portions of one or both of the frames into interlapping relation with the other frame, and such bending operations are not feasible where molded or cast materials are employed. The use of molded or cast materials, particularly certain of the recently developed plastic materials, for belt buckle constructions includes numerous advantages, including a saving in the consumption of metal, and accordingly it is a further object of this invention to provide a slide buckle construction which may be formed either in whole or in part from molded or cast materials such as plastics.

In carrying out the invention in one form a buckle is provided comprising a frame member formed of molded plastic material, which frame member is shaped to enclose and slidably support a cooperating slide member formed of metal or any other suitable material. Preferably both the frame member and the slide member are provided with side bars connected together by spaced-across bars defining strap-receiving openings and co-operating cross bars on the frame and the slide are arranged to clamp the strap, upon the application of tension thereto, in desired adjusted positions.

In a specific embodiment of the invention the plastic frame member comprises a pair of interfitting members adapted to be permanently secured together so as to support the slide there-

between for limited sliding movement, and one of the cross bars on the plastic frame member is so formed as to insure a wedging clamping action and so correlated with the slide member as to prevent improper threading of the buckle.

For a more complete understanding of the invention reference should now be had to the drawing in which:

Fig. 1 is a front elevational view of a buckle embodying this invention applied to a belt or strap, the belt or strap being shown fragmentarily;

Fig. 2 is a sectional view taken substantially along the longitudinal center line of Fig. 1 and illustrates the buckle in threaded position.

Fig. 3 is a sectional view similar to Fig. 2, but showing the buckle in clamping position.

Fig. 4 is a transverse sectional view of one of the frame members of the buckle taken substantially along the line 4—4 of Fig. 1.

Fig. 5 is a perspective view of the slide member employed in the buckle of Fig. 1.

Fig. 6 is a perspective view of one of the plastic frame members of the buckle of Fig. 1 viewed from the rear side thereof, and

Fig. 7 is a perspective view of a second plastic frame member which forms a closure cap or insert adapted to interfit with the frame member of Fig. 6.

Referring now to the drawing, the invention as shown is embodied in a buckle comprising a main frame member 10 formed of suitable molded or cast material such as plastic, comprising a pair of spaced apart side bars 11 and 12 connected by a plurality of spaced cross bars 13, 14 and 15 so as to form a pair of strap-receiving openings 16 and 17. The under surface of the cross bar 13, as shown best in Figs. 2 and 3, is formed to provide a substantially flat, inclined surface 18, and a curved bulging surface 19, the purpose of which will be more fully described hereinafter. As shown best in Fig. 4, portions of the side bars 11 and 12 and the cross bars 13 and 14 of the frame 10 are cut away in a manner, which will be more fully described hereinafter, to provide a generally rectangular recess or opening (shown best in Fig. 6) for receiving a slide member 20 (Fig. 3) and a closure cap or insert member 21 (Fig. 7), which is in the form 50 of a second plastic frame member, and serves, when assembled with the member 10, to provide longitudinal slots for retaining the slide member 20 permanently within the frame 10.

As shown in Fig. 3, the slide member 20, which 55 may be formed of metal or any other suitable

material having the necessary strength, comprises spaced apart side bars 22 and 23 connected by cross bars 24 and 25, which are spaced apart to provide a strap-receiving slot 26. As shown, the cross bar 25 is embossed downwardly over a central portion thereof, and the other cross bar 24 is provided with an upstanding flange 27. The closure cap 21, as shown best in Fig. 7, comprises spaced apart side bars 28 and 29 connected by spaced cross bars 30 and 31, so as to provide a strap-receiving slot 32, and it will be understood that when the frames 10, 20 and 21 are assembled and disposed in threaded relation, as shown in Fig. 2, the various strap receiving slots 16, 26 and 32 will be in aligned relation so as to permit the threading of a strap or belt therethrough.

The cross bar 30 on the frame member 21 is provided adjacent its outer edge with an upstanding flange 33, which is notched out intermediate the ends thereof to provide end blocks 34, and the cross bar 31 on the frame 21 is provided at its outer edge with an upstanding flange 35. Likewise, as shown best in Fig. 7, the side bars 28 and 29 of the frame member 21 are provided at their outer edges with upstanding flanges 36 and 37, respectively, having arcuately shaped upper edges.

In order to receive the frame or insert member 21 in interfitting relation so as to slidably support the slide 20 therebetween, the cross bar 14 on the frame member 10 is provided, as shown best in Figs. 2 and 4, with a transversely extending groove 38 for receiving the flange 33, and with a downwardly extending flange 39 which fits within the notched out portion of the flange 33 between the end blocks 34. Similarly the cross bar 13 on the frame member 10 is provided with a transversely extending groove 40 for receiving the upstanding flange 35 on the cross bar 31 of the frame 21, and a downwardly extending flange 41 on the cross bar 13 is adapted to overlap the inner edge of the flange 35. Extending longitudinally of the side bars 11 and 12 between the grooves 38 and 40 are suitable slots 42 and 43 (Fig. 4) for receiving the upstanding flanges 36 and 37 on the side bars of the frame 21. It will thus be seen that the outer walls of the grooves 38 and 40 and the outer walls of the slots 42 and 43 define a substantially rectangular recess in the rear surface of the frame 10, which recess extends around the strap-receiving slot 16 and is adapted to receive the slide member 20 and the insert frame 21.

The portion of the side bars 13 and 14 intermediate the grooves 42 and 43 and the respective inner edges of the side bars 11 and 12 are partially cut away to provide guide surfaces 44 and 45 which define longitudinal slots in the inner faces of the side bars 11 and 12 for receiving the slide member 20 when this slide member is positioned within the frame 10. This slide member is preferably positioned with the upper surfaces of the side bars 22 and 23 thereof respectively engaging the guide surfaces 44 and 45 of the longitudinal slots, and with the lower surfaces of the side bars 22 and 23 resting on the upper surface of the side bars 28 and 29 on the insert or frame member 21. The flanges 33, 35, 39 and 41 on the frame members 21 and 10 are slightly greater in height than the thickness of the side bars 22 and 23 on the frame member 20, and thus when the plastic frame members 10 and 21 are assembled together in interfitting relation, guide slots are formed extending longitudinally of the frame 10 for supporting the slide 20 for

limiting sliding movement therein. As shown best in Fig. 2, the flange 39 on the cross bar 14 of the frame 10 and the cross bar 31 on the frame 21 respectively form stops to limit the rearward and forward movement of the slide 20 within the frame 10.

Assembly of the buckle is accomplished merely by inserting the slide member 20 into the frame 10 in the above described relation, and then securing the closure cap or insert 21 in position permanently to retain the slide member within the main frame 10. Although any suitable securing means such as cement may be employed to secure the members 21 and 10 together, it is preferable to coat the cooperating interfitting surfaces of these two members with a binding material, such as acetone, which combines with the material of the frames to provide a substantially unitary or welded construction so that the two frame members become in effect a single integral plastic structure.

In the drawing the buckle is shown as applied to a belt or strap having one end 50 thereof looped about the cross bar 15 on the frame 10, so as to pass through the strap-receiving opening 17, the belt being secured upon itself by sewing, gluing or any other desired securing means. The opposite or free end 51 of the belt, when the buckle is in the threading position shown in Fig. 2, may then be threaded upwardly through the strap-receiving openings 32, 26 and 16 in the members 21, 20 and 10, respectively, which strap-receiving openings are in alignment in this position of the slide. It will be apparent that even though the slide is in its extreme right-hand position, as viewed in Fig. 2, threading of the free end of the strap otherwise than through the above indicated aligned openings is prevented by reason of the fact that the bulging face 19 of the cross bar 13 on the frame 10 so closely approaches the cross bar 25 on the slide as to prevent threading of the strap therebetween. Obviously in any other position of the slide the cross bar 25 more closely approaches the bulging surface 19 and improper threading of the buckle is prevented in all positions.

When the belt or strap has been threaded through the buckle, as shown in Fig. 2, the application of tension to the strap will cause the threaded portion of the strap adjacent the free end 51 to engage the lower rounded surface of the cross bar 25 on the slide 20, which cross bar 25 constitutes the pull-up bar of the buckle. It will be noted that the pull-up bar 25, by reason of its downward embossment, is disposed in a plane below the normal plane of the slide 20, and it will similarly be noted that the upstanding flange 27 on the cross bar 24 of the slide extends above the plane of the slide. Consequently the belt or strap is sufficiently deflected from a straight path so that the application of tension does not merely pull the free end of the strap through the strap-receiving openings, but instead exerts a force on the pull-up bar 25 which tends to move the slide 20 in a left-hand direction. At the same time the tension on the end 50 of the strap tends to pull the frame 10 in right-hand direction due to the fact that this portion 50 is looped about the cross bar 15. Consequently relative sliding movement occurs and in Fig. 3 the parts of the buckle are shown in their respective clamping position. In these clamping positions the slide 20 is so positioned relative to the frame 10 that the strap is clamped therebetween with a wedging clamping action.

Thus it will be seen that in Fig. 3 the belt is engaged at three points, one on the slightly sloping surface 18, one on the bulging surface 19, and the third along the upper edge of the flange 21 on the cross bar 24 of the slide, which cross bar and flange constitute the clamping bar of the slide.

The clamping effect obtained is substantially the same as that which would be encountered if the under surface of the cross bar 13 extended in a flat inclined plane between the two points of engagement with the strap. By providing the particular configuration shown, however, the buckle not only prevents improper threading due to the bulging surface 19, but also tends to cause the free end of the strap to lie substantially flat after passing through the buckle. It will thus be seen that the belt or strap tends to follow the plane of the portion 18 which extends at only a slight angle (approximately 18°, for example, with the plane of the buckle). If desired, the surface 18 may extend parallel to the plane of the buckle, as is described and claimed in my copending application Serial No. 449,236, filed July 1, 1942, now Patent No. 2,334,462, granted Nov. 16, 1943, and entitled Buckles. I prefer, however, to employ the slightly inclined surface, shown, as a somewhat easier release of the buckle is accomplished with this slight inclination.

To release the belt or strap for movement to another desired position, or for withdrawal of the free end 51 from the buckle, it is necessary only to exert a slight pull in a right-hand direction, as viewed in Fig. 3, on the free end. This, of course, may be accomplished either by a straight pull on the free end of the belt, or by pulling the free end around the edge of the cross bar 13. Since the pull-up bar 27 on the slide 20 slightly underlies the cross bar 13 when in clamping position, pulling the end of the strap around the edge of the cross bar 13 tends to move the slide rearwardly and to effect release of the belt or strap.

While a particular embodiment of the invention has been shown, it will be understood, of course, that it is not desired that the invention be limited thereto since modifications may be made, and it is, therefore, contemplated by the appended claims to cover any such modifications as fall within the true spirit and scope of the invention.

Having thus described the invention, what is claimed and desired to be secured by Letters Patent is:

1. A slide buckle comprising a frame formed of molded plastic material, a slide member, said frame and said slide member having side bars and cross bars defining strap-receiving openings therethrough to receive a strap, said side bars of said molded frame having longitudinal slots in the inner faces thereof to receive the side bars of said slide member, said slots being substantially rectilinear to restrain said slide member against transverse or tilting movement and support said slide member in longitudinal sliding relation to said molded frame, said slide member being entirely confined within said molded frame, one of said cross bars on said molded frame having an underlying strap-engaging surface for cooperating with one of said cross bars on said slide member to clamp in adjusted position a strap threaded therebetween.

2. A slide buckle for association with a strap comprising a pair of frames each having side bars and spaced apart cross bars defining strap-

receiving openings, said frames having complementary embossed and grooved portions to be fitted together and secured in overlapping relation, said frames when assembled having longitudinal slots in the inner faces of the side bars thereof, and a strap-gripping slide within said frames having side bars and cross bars, said side bars of said slide engaging said longitudinal slots for movement therein.

3. A slide buckle for releasably securing a strap in an adjusted position, said buckle comprising interfitting outer and inner plastic frames and a slide member entirely contained between said frames, said frames and said slide member having spaced side bars and cross bars defining strap-receiving openings to receive a strap, the outer of said frames having peripheral embossments and grooves extending about one of said openings to form a slide-receiving recess, and the inner of said frames having complementary peripheral embossments and grooves to interfit with said embossments and grooves on said outer frame to retain said slide member and strengthen said buckle when the inner frame is secured in interfitting relation within said recess.

4. A slide buckle comprising a pair of nested frames formed of molded plastic material secured together to confine a slide member therebetween, one of said frames being rearwardly recessed to receive the other of said frames in nested relationship, said frames and said slide member having side bars and cross bars defining strap-receiving openings therethrough, said frames cooperating to define longitudinal slots to support said slide member entirely therewithin.

5. A slide buckle comprising a pair of nested frames formed of molded plastic material secured together to confine a slide member therebetween, one of said frames being rearwardly recessed to receive the other of said frames in nested relationship, said frames and said slide member having side bars and cross bars defining strap-receiving openings therethrough, said frames cooperating to define longitudinal slots to support said slide member entirely therewithin, and said cross bars on said frames forming stops for limiting the longitudinal movement of said slide member in said slots.

6. A slide buckle comprising a frame formed of molded plastic material, a slide member, said frame and said slide member having side bars and cross bars defining strap-receiving openings therethrough to receive a strap, said side bars of said frame having longitudinal slots therein to receive the side bars of said slide member and support said slide member in sliding relation to said frame, one of said cross bars on said frame having a strap-engaging surface including a protruding bulge for cooperating with one of the cross bars on said slide member to clamp in adjusted positions a strap threaded therebetween.

7. A slide buckle comprising a frame formed of molded plastic material, a slide member, said frame and said slide member having side bars and cross bars defining strap-receiving openings therethrough to receive a strap, said side bars of said frame having longitudinal slots therein to receive the side bars of said slide member and support said slide member in sliding relation to said frame for movement between a threading position and a clamping position, one of said cross bars on said frame having a strap-engaging surface including a protruding bulge for cooperating with one of said cross bars on said

slide member to clamp in adjusted position a strap threaded therebetween, another cross bar on said slide member underlying said bulge when said slide member is in said clamping position, said other cross bar on said slide member cooperating with said bulge to prevent improper threading of the strap through said buckle with said slide member in said threading position.

8. A slide buckle comprising a frame formed of molded plastic material, a slide member, said slide member and said frame having spaced side bars and interconnecting cross bars defining strap-receiving openings therethrough to receive a strap, said cross bars on said frame comprising end bars and an intermediate bar, one of said end bars having a strap-engaging under surface for cooperation with said slide to clamp a portion of a strap therebetween upon the application of tension to said strap, said intermediate bar forming a stop for positioning said slide in threading position.

9. A slide buckle for association with a strap comprising a pair of frames having interfitting surfaces secured together to form a buckle casing having spaced side bars and cross bars defining strap-receiving openings therethrough to receive a strap, said interfitting frames being secured together at their edges only to leave a central slide-receiving space therebetween, the side bars of said frames having longitudinal slots therein, and a slide supported in said longitudinal slots and having cross bars, one of said cross bars having an upstanding strap-engaging flange extending above the plane of said longitudinal slots and the other of said cross bars being downwardly embossed to project below the plane of said longitudinal slots, one of the cross bars of said buckle casing having a protruding strap-engaging surface above the plane of said longitudinal slots and extending over a portion thereof, so that in clamping position of said slide one of the cross bars thereof cooperates with said protruding strap-engaging surface to clamp a

strap therebetween and the other of said cross bars on said slide underlies said protruding surface.

10. A buckle for releasably securing a strap in an adjusted position, said buckle comprising a pair of interfitting plastic frames secured together to form a unitary buckle casing having a strap-receiving slot extending therethrough, each of said frames having side bars provided with grooves cooperating to define longitudinal slots in the inner sides of said side bars, and a strap-engaging slide movably supported in said longitudinal slots within said buckle casing for substantially rectilinear motion into engagement with said strap to retain said strap in adjusted position.

11. A slide buckle for releasably securing a strap in an adjusted position, said buckle comprising a frame member having side bars and cross bars defining strap-receiving openings therethrough to receive a strap, said side bars and cross bars being recessed on one surface of said frame, a slide positioned in said recess and having strap-engaging cross bars, and an insert frame member having edges for interfitting engagement with the edges of said recess to be nested therein and retain said slide in place, one of the cross bars on said frame having a protruding strap-engaging portion and one of the cross bars on said slide having a downwardly embossed strap-engaging portion, said last mentioned cross bars cooperating to prevent improper threading of said strap through said buckle.

12. A strap-gripping slide for buckles comprising an elongated strip of sheet material having side bars and cross bars defining a strap-receiving opening therethrough to receive a strap, one of said cross bars having an upwardly directed strap-engaging portion extending above the plane of said slide and the other of said cross bars having a downwardly directed strap-engaging portion extending below said plane.

PAUL W. WHITE.
